(57) CLAIM

The ornamental design for an open grill as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of an open grill;

FIG. 2 is a front view thereof;

FIG. 3 is a front perspective view thereof;

FIG. 4 is a top view thereof;

FIG. 5 is a rear view thereof;

FIG. 6 is a bottom view thereof;

FIG. 7 is a left side view thereof; and,

FIG. 8 is a right side view thereof.

The “GreenPan” logo shown in the drawings, and forming no part of the claim, is a registered trademark of Apollo Topco, besloten vennootschap.

The parts of the photographic renderings shown faded out form no part of the claimed design.

1 Claim, 8 Drawing Sheets
